ABSTRACT OF THE DISCLOSURE

This invention relates generally to a razor having an openable blade-holding head, a hollow handle extending therefrom, a shaft moveable within said handle and actuating means associated with said handle for incrementally rotating an indicator ring having numerical indicia thereon whereby the said numerical indicia is successively changed with each successive opening of the head.

This invention relates generally to razors, and is especially concerned with improvements in razors of the shave-counting type.

It is an important object of the present invention to provide a shave-counting razor which is entirely automatic in operation, the number of shaves being indicated by the razor without any special procedure or effort by the user.

It is a more particular object of the present invention to provide a shave-counting razor of the type described wherein an indicator is automatically stepped or operated upon full opening of the blade-holding head for cleaning between shaves; while partial opening of the head, as for rinsing during a shave, does not affect the counter.

It is still a further object of the instant invention to provide a razor wherein the number of shaves per blade is automatically counted, and wherein the changing of a blade and reversion of the counter to zero is quickly and easily effected by a simple finger pushing operation.

It is still a further object of the present invention to provide a shave-counting razor having the advantageous characteristics mentioned in the preceding paragraphs, which is extremely simple in construction, automatic in operation, may be economically manufactured for sale at a reasonable price, and which is durable and entirely reliable throughout a long useful life.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

FIGURE 1 is a longitudinal elevational view showing a razor constructed in accordance with the teachings of the present invention, with the blade-holding head in closed condition;

FIGURE 2 is a top perspective view showing the razor of FIGURE 1 with the head in an open condition;

FIGURE 3 is a partial longitudinal sectional view taken generally along the line 3—3 of FIGURE 1;

FIGURE 4 is a transverse sectional view taken generally along the line 4—4 of FIGURE 3;

FIGURE 5 is a transverse sectional view taken generally along the line 5—5 of FIGURE 3;

FIGURE 6 is a partial longitudinal sectional view similar to FIGURE 3, but illustrating the head open condition; and

FIGURE 7 is a partial longitudinal sectional view simi-

lar to FIGURE 6, but showing a slightly modified embodiment of the present invention.

Referring now more particularly to the drawings, and specifically to FIGURES 1 and 2 thereof, a shave-counting razor is there generally designated 10, and includes a blade-holding head 11 disposed transversely on one end of an elongate hollow handle 12. The handle 12 extends from the head 11 and includes, an elongate hollow tube 13, having one end fixed to the head 11, and, a rotary actuating knob 14 carried by the remote or distal end of the tube 13. The knob 14 is rotatably carried, as by a journal connection 15 on the distal end of tube 13, see FIGURE 3.

Referring again to FIGURE 3, the handle tube 13 is provided with a thru opening 18, which may be of generally rectangular configuration, as illustrated, or otherwise if desired. A window 19, say of transparent plastic or other light-permeable material, is located in the opening 18 to close the latter while affording visual access therethrough. The window 19 is retained in the opening 18 by any suitable means, such as a retainer lip 20 extending interiorly of the tube 13, to prevent outward removal of the window while permitting inward displacement thereof, as by finger pressure of a user.

Along its upper edge, the window 19 is provided with a flange 21 extending inwardly into the interior of tube 13, and a tooth 22 depends from the flange 21, for a purpose appearing presently. The lower edge of window 19 is similarly provided with an inwardly extending flange 23, the lower and upper flanges 23 and 21 combining to define an inwardly facing recess 24.

Disposed longitudinally within the tube 13, generally axially thereof, is an elongate member of shaft 26 of sectional construction including a main part 27 in the tube 13 and extending into the actuating knob 14. The shaft 26 includes a head-connection part 28 for attachment to the head 11 to operate the latter, and is swivelly connected, as by a swivel joint 29, to the adjacent end of the main shaft part 27. The head-connection shaft part 28 may be constrained to pure axial, longitudinal movement, as by a pin 30 fixed to the tube 13 and projecting into a longitudinally extending groove 31 of the shaft part 28. Thus, the shaft part 28 may shift longitudinally the pin 30 riding in the groove 31, but is constrained against rotative movement. The main shaft part 27 is movable both longitudinally and rotatively, a pin 33 projecting inward from the tube 13 and having its inner and engaging in a cam slot 34, say of generally spiral configuration. In order to effect longitudinal and rotative movement of shaft part 27, the knob 14 is provided with a crosspin 35 extending through a diametral slot 36 in the shaft part 27. The slot 36 is of a length permitting movement of the shaft part 27 relative to the cross pin 35. Hence, upon rotation of knob 14, the shaft part 27 is rotated by the pin 35 in slot 36, and the shaft part is free to move longitudinally as determined by the cam action of pin 33 in slot 34. This shifts the shaft part 27 longitudinally in opposite directions, to raise and lower the shaft part 28 which is rotatably affixed to shaft part 27 and the swivel joint 29, for opening and closing the head 11. If desired, other suitable means may be employed for opening and closing the head 11.

Rotatably circumscribed about the shaft part 27 is an annular indicator member or ring 38 having numerical indicia on its periphery and adjacent to the window 1 for visual presentation of the indicia through the said window. Further, the indicator ring 38, while rotatably and slidably longitudinally relative to the shaft part 27, is received in the recess 24 of the window 19, and theretofore maintained in position longitudinally of the handle tube 13. Suitable resilient means, such as a coil spring 40, ma-

be connected between the indicator ring 38 and the tube 13, to resiliently and yieldably maintain the ring in a predetermined position of its rotative movement. More particularly, the ring 38 may be yieldably and resiliently urged by the spring 40 to a position of its rotative movement with a particular numeral indicia exposed through the window 19.

On the underside of indicator ring 38, as seen in FIGURE 3, there is an annular array of depending teeth 41, say of triangular or ratchet-tooth configuration. On the upper side or end of ring 38 may be provided an annular array of upstanding teeth 42, which may also be of generally triangular, or ratchet-tooth configuration. As in the illustrated embodiment, the lower group of teeth 41 may be arranged in an annulus concentric with and having a smaller diameter than the annular array of upper teeth 42. Further, the depending lug or tooth 22 carried by window 19 is normally located in the path of the upper group of teeth 42 for abutting engagement with respective latter teeth to limit rotative movement of indicator ring 38 in one angular direction. However, the lug or tooth 22 is displaceable out of the path of teeth 42, as by inward movement of the window 19 under finger pressure of the user, to permit return of the indicator ring 38 to its original position under the resilient force of spring 40.

The operating shaft part 27 carries a lug or abutment 44 for movement with the shaft into engagement with the lower depending teeth 41. That is, upon rotation of knob 14 to effect upward shifting and axial rotation of shaft part 27, the lug 44 engages one of the teeth 41 to effect an incremental rotational movement of indicator ring 38. The lug or tooth 22 of window 19 is configured to ride over one of the teeth 42 upon this incremental rotation of ring 38, as by flexure of the lug 22 or displacement of the window. Hence, the lug 22 is then in holding engagement with the next adjacent tooth 42. This incremental movement of indicator ring 38 is illustrated in FIGURE 6, the position of lug 44 being shown in phantom in FIGURE 5. Upon return of the shaft part 27 to its original position of FIGURE 3, the lug 22 retains the indicator ring 38 in its incrementally rotated position against the action of coil spring 44.

The above-described operation is that for fully opening and closing the head 11, as for removal and replacement of a blade, and thorough rinsing of the razor. Sufficient opening of the head 11 to effect rinsing, but without blade replacement, may be effected without incrementally rotating the indicator wheel 38, as the head may be open sufficiently for rinsing without lug 44 engaging a tooth 41.

Thus it will be appreciated that each successive full rinsing of the head 11, as at the end of each particular shaving procedure, will effect an incremental rotative displacement of indicator wheel 38, so that the indicia thereof presented through window 19 will record the number of shaves performed. Upon replacement of the blade, it is only necessary to depress the window 19 inward to release the upper group of indicator-wheel teeth 42 from lug 22, whereupon the indicator wheel 38 returns to its starting position under the force of the spring 40. The holding action of lug 22 with respect to a tooth 42 may best be seen in FIGURE 4.

A slightly modified embodiment is illustrated in FIGURE 7, say for use in razor constructions wherein the operating shaft may be constrained against rotation and limited to longitudinal shifting movement.

The handle tube 13a, as shown in FIGURE 7, may be essentially similar to the handle tube 13 of FIGURE 3, and an actuating knob 14a is illustrated in threaded engagement with an operating shaft 26a. The operating shaft 26a may be of an integral construction, and will be constrained against rotation by its attachment to transverse member 50 (see FIGURE 2) movably attached to the blade holding head 11. The transverse member 50 is free to move vertically up or down by vertical movement of the operating shaft 26a. Said member 50, however, is con-

strained against rotative movement by slots provided in the base 51 of the shaving head 11 in a known manner. Referring to FIGURE 2, the member 50 will have end members 53 pivotally engaging the lid portions 52 of the head 11 thereby facilitating the opening and closing of the lids 52 by the up and down movement of the shaft 26a in a known manner. Thus, the shaft 26a is limited to longitudinal movement responsive to rotation of knob 14a, and the shaft 26a is constrained against rotation.

Provided in the handle tube 13a is an opening 18a receiving a window 19a, which may be essentially identical to the window 19 of the first-described embodiment.

An indicator ring 38a may be slidably and rotatably circumposed about the shaft 26a, constrained against longitudinal movement by engagement in the window 19a, and otherwise substantially identical to the first-described indicator ring 38. Suitable resilient means, such as a coil spring 40a may be connected between the indicator ring 38a and handle tube 13a to urge the ring toward a starting position of its rotative movement.

Rotatably and slidably circumposed about the shaft 26a is an open-ended tubular member or sleeve 46 provided in its outer surface with a cam slot 47. A pin 48 projects interiorly from the handle tube 13a into sliding engagement in the cam slot 47, and an additional pin 49 may be fixed to the shaft 26a just below the lower end of sleeve 46 for engagement with the latter.

Thus, upon upward longitudinal shifting of shaft 26a, pin 49 engages sleeve 46 to move the sleeve upward with the pin, while cam pin 48 slides in groove 47 to effect rotative movement of the said sleeve relative to the shaft 26a.

Carried on the upper end of the sleeve 46 is a lug 44a engageable upon upward and rotative movement of the sleeve to engage one of the depending teeth 41a and thereby effect incremental rotation of indicator wheel 38a. The indicator wheel is held in its incrementally rotated position by interengagement of window tooth 22a with upper ring teeth 42a, in the same manner as described hereinbefore; and, the indicator wheel 38a may be returned to its initial angular position by inward depression of the window 19a.

From the foregoing, it is seen that the present invention provides a razor construction of the shave-counting type which fully accomplishes its intended objects and is well adapted to meet practical conditions of manufacture and use.

Although the present invention has been described in some detail by way of illustration and example for purposes of clarity of understanding, it is understood that certain changes and modifications may be made within the spirit of the invention and scope of the appended claims.

What is claimed is:

1. A shave counting razor comprising a blade holding head disposed transversely on one end of an elongate hollow handle, said handle extending from said head and including an elongate hollow tube having one end fixed to said head and a rotary actuating knob rotatably affixed to the other end of said hollow tube, a through opening in said hollow handle, a window located in said opening, means for retaining said window in said opening to prevent outward removal of said window while permitting inward displacement thereof, a flange on said window extending inwardly into the interior of said hollow tube, a lug depending from said flange, an elongate shaft extending longitudinally within said hollow tube, said elongate member including a first shaft extending at one end into said actuating knob and being swivelly connected at its other end to a second shaft, said second shaft constrained to pure axial longitudinal movement, said first shaft movable both longitudinally and rotatably, a cam slot of generally spiral configuration in said first shaft, a pin projecting inward from said tube and having its inner end engaging in said cam slot, a diametral slot in said

first shaft adjacent said one end thereof, a cross-pin in said knob extending through said diametral slot, an annular indicator ring having numerical indicia on its periphery rotatably circumscribed about said first shaft and adjacent said window for visual presentation of the indicia through said window, said indicator ring being rotatable relative to said first shaft, resilient means connected between said indicator ring and said tube to resiliently and yieldably maintain said ring in a predetermined position of its rotative movement, an annular array of depending teeth on the underside of said indicator ring, an annular array of upstanding teeth on the upper side of said ring, said depending lug carried by said window normally located in the path of said upstanding teeth for abutting engagement with respective teeth to limit rotative movement of said indicator ring in one angular direction, an abutment on said first shaft below the position of said ring for movement with said first shaft into engagement with said depending teeth to effect an incremental rotational movement of said ring, said lug being configured to ride over one of said upstanding teeth upon rotational movement of said ring.

2. A shave counting razor according to claim 1, further including a longitudinally extending groove in said second shaft, and a pin fixed to said tube and projecting into said groove to constrain said second shaft against rotative movement.

3. A shave counting razor according to claim 1, a recess in said window, said indicator ring being received in said recess to thereby maintain said ring in position longitudinally of said tube, said resilient means connecting between the indicator ring and said tube being a coil spring.

4. A shave counting razor according to claim 1, depending teeth and said upstanding teeth being of ratchet-tooth configuration and said depending teeth arranged in an annulus concentric with and having a smaller diameter than said annular array of upstanding teeth.

5. A shave counting razor comprising a blade holding head disposed transversely on one end of an elongate hollow handle, said handle extending from said head and including an elongate hollow tube having one end fixed to said head and a rotary actuating knob rotatably affixed to the other end of said hollow tube, a thru opening in said hollow tube, a window located in said opening, means for retaining said window in said opening to prevent outward removal of said window while permitting inward displacement thereof, a flange on said window

extending inwardly into the interior of said hollow tube, a lug depending from said flange, an elongate shaft extending longitudinally within said hollow tube, one end of said elongate member extending into said actuating knob for threaded engagement therewith, the other end of said elongate member attached to a transverse member in said head constrained to vertical movement only, an open-ended tubular member rotatably and slidably circumscribed about said elongate member, a cam slot of generally spiral configuration in said tubular member, a pin projecting inward from said tube and having its inner end engaging in said cam slot, a second pin affixed to said elongate member below said tubular member to effect movement of the latter upon movement of said elongate member, an annular indicator ring having numerical indicia on its periphery rotatably circumscribed about said elongate member and adjacent said window for visual presentation of the indicia through said window, said indicator ring being rotatable relative to said elongate member, resilient means connected between said indicator ring and said tube to resiliently and yieldably maintain said ring in a predetermined position of its rotative movement, an annular array of depending teeth on the underside of said indicator ring, an annular array of upstanding teeth on the upper side of said ring, said depending lug carried by said window normally located in the path of said upstanding teeth for abutting engagement with respective teeth to limit rotative movement of said indicator ring in one angular direction, a second lug on the upper edge of said tubular member, whereby the vertical movement of said elongate member will effect both vertical and rotative movement of said tubular member and said second lug to effect an incremental rotational movement of said ring, said first lug being configured to ride over one of said upstanding teeth upon rotational movement of said ring.
